UNITED STATES PATENT OFFICE.

WILLIE O. BESAW, OF REEDLEY, CALIFORNIA.

FUSE ELEMENT.

Application filed May 4, 1923. Serial No. 636,564.

To all whom it may concern:

Be it known that I, WILLIE O. BESAW, a citizen of the United States, residing at Reedley, in the county of Fresno and State of California, have invented certain new and useful Improvements in Fuse Elements, of which the following is a specification.

In carrying out the present invention, it is my purpose to provide a fuse element 10 that may be inserted into the usual sockets of the fuse boxes of house wire systems in conjunction with a burnt out fuse plug for again completing the circuit between the terminal wires of the wiring system, the 15 primary object of the invention being the provision of such a fuse element that is extremely simple of construction, and one that may be manufactured and marketed at substantially one-tenth or more of the 20 cost of the usual fuse plugs now universally used.

The nature and advantages of the invention will be better understood when the 25 following detailed description is read in connection with the accompanying drawing, the invention residing in the construction, combination, and arrangement of parts as claimed.

In the drawings forming part of this application, like numerals of reference indicate similar parts in the several views, and wherein:

Figure 1 is a side elevation of my improved fuse element, the same being shown 35 in position within a socket of a fuse box, and maintained therein through the medium of a burnt out well known form of fuse plug.

Figure 2 is a plan view of my fuse element per se, and

Figure 3 is a detail longitudinal cross section upon the line 3—3 of Figure 2.

Referring to the drawing, and particularly to Figure 1, 5 indicates a socket element of the usual insulating material provided with an internal metallic lining 6, as well as a contact element 7 insulated from the lining 6, this contact element and lining being of course in circuit with the feed and neutral wire respectively, of the house wiring system. Also in this figure, 8 indicates a fuse plug of conventional form, it being of course understood that the socket element 5 and plug 8 do not constitute any portion of my invention, the

same being merely shown for permitting of the more adequate disclosure of the relationship of my invention therewith. My fuse element per se, designated generally 9 is in the form of a disk of a 60 diameter equivalent to the internal diameter of the lining 6 of the socket member 5. This fuse element comprises a pair of disks 10 and 11 of mica, or other non-insulating material, between which is a 65 length of fusible wire 12 preferably of serpentine shape. One end of this fusible wire 12 is extended around the central portion of a lead rivet 13 that serves as a connecting means for the pair of disks 10 and 11. Surrounding the edges of these disks 10 and 11 is a clamped ring 14 of some suitable shaped metal.

In practice, when one of the usual fuse plugs 8 of the house wiring system is burnt 75 out, the same is removed from the socket member 5, and my fuse element positioned therein as shown in Figure 1. One side of the lead rivet 13 will engage the contact 7 of the socket element 5, while the so ring 14 will have close contact with the adjacent portion of the plug lining 6. After the fuse element has been positioned within the socket, the burnt out plug is again inserted therein, and serves as a means for 85 maintaining my fuse element in proper position within the socket. It will of course be understood that the usual contact upon the lower end of the plug 8 will engage the opposite end of the rivet 13 for thereby completing the circuit between the contact 7 and lining 6. Any overload upon the line will occasion a burning out of the fusible wire 12, after which the plug 8 may be removed as well as the fuse element, and another fuse element positioned 90 in its stead.

In view of the above description, it will at once be apparent that I have provided a highly useful form of article that may 100 be employed in lieu of the wellknown type of fuse plug after the original fuse plugs have become burnt out, and even though I have herein shown and described my article as being of a certain particular construction, it is nevertheless to be understood that minor changes may be made therein, without departing from the spirit and scope 105 of the invention as claimed.

Having thus described my invention, 110

what I claim as new, and desire to secure by Letters-Patent, is:

1. In combination with a socket element and a burnt out fuse plug, a wire adapted to be positioned within the socket and maintained therein by said burnt out fuse plug, the opposite ends of the wire being in circuit with the usual contact element and lining of said socket element.
- 10 2. In combination with a socket element and burnt out fuse plug, means adapted for positioning within said socket element and maintained therein by said burnt out fuse plug for completing the circuit between the usual contacts of said socket element.
- 15 3. In combination with a socket element and burnt out fuse plug, a disk adapted for insertion within said socket element and adapted to be maintained therein by said
- 20 burnt out fuse plug, said disk including a

fusible wire and means for contacting the ends of said fusible wire with the usual contacts of said socket element.

4. A fuse comprising a pair of discal insulating members, a circular conductor 25 peripherally holding the insulating members together, a conductor member passing concentrically through the discs, and a fusible member passing between the discs to connect the conductors.

5. A fuse comprising an annular conductor adapted to engage the outer wall of a socket, a pair of insulating discs supported by the annulus, a contact member concentric of the discs, and a fusible wire between 35 the discs electrically connecting the disc with the annulus.

In testimony whereof I affix my signature.

WILLIE O. BESAW.
